JACK

Edmund Aron, Chicago, Ill., assignor to Moto-Sway Corporation of America, a corporation of Illinois

Application August 23, 1939, Serial No. 292,179

3 Claims. (Cl. 74—592)

This invention relates to jacks which are employed for the purpose of vibrating automobiles during the greasing operation. Such jacks are commonly mounted in lifting engagement with the side frame bars of the chassis to alternately take the weight of the chassis and body off, and restore it to, the springs, so as to facilitate the introduction of grease between the leaves of the springs and to the shackle bolts and its distribution over the surfaces to be lubricated.

Many devices of this character employ pneumatic motors for operating the jack, with complicated automatic valve mechanisms for admitting and exhausting the motive fluid and cushioning the down stroke of the jack plunger; and one object of this invention has been to get rid of such complicated and expensive mechanisms and provide a very simple and relatively inexpensive jack capable of being actuated by an ordinary electric motor. Another object has been to provide, in a jack of this type, a device having the double function of (1) assisting the motor in effecting the lifting movement of the jack and (2) cushioning the down movement. In the preferred form of the invention this device comprises a tensioned spring having a force when fully tensioned approximately equal to the gravity force of the load associated with the power transmission line from the motor in such a manner that during the lifting operation of the jack it aids the motor, and during the lowering operation of the jack it opposes the gravity force of the load and cushions the down stroke. Preferably also the portion of the transmission gearing from the motor to the part acted on by the said spring is self-locking against movement under the thrust of the load in one direction and of the spring in the other; so that, for the lifting movement, only enough power is required of the motor to overcome the friction of the self-locking gearing and supplement the power of the spring, and, for the lowering movement, only enough power is required of the motor to overcome the friction of the self-locking gearing and permit the weight of the load to restore the spring to its maximum tension.

An approved embodiment of the invention is illustrated in the accompanying drawings, in which—

Fig. 1 is an elevation of the jack and its motor, in vertical section through the outer casing, and showing the lower end portion of the plunger.

Fig. 2 is a vertical section through the upper portion of the jack plunger, the head and saddle

on the upper end of the plunger, and the mechanism for adjusting the saddle to a fit on the part of the automobile engaged thereby; this view being a vertical extension of the parts appearing in Fig. 1.

Fig. 3 is a vertical axial section, taken on the line 3—3 of Fig. 1.

Fig. 4 is a horizontal section, taken on the line 4—4 of Fig. 3.

10 Referring to the drawings, 10 designates an upright jack casing which preferably is integral with the base support 11, on which support 11 is mounted an electric motor 12. The upper end of the jack casing is closed by a removable cap or cover 13 secured thereto by screws 14, and in and centrally of the cover 13 is fitted a bearing boss 15 for a vertically reciprocable plunger, the lower section of which is designated by 16. The lower end of the plunger section 16 is secured in 15 a ring 17 that constitutes the central portion of a cross-head 18. The ends of the cross-head 18 are connected by depending links 19 to a pair of cranks 20 formed in a crank shaft 21 that is journalled at its ends in bearings 22 carried by lateral bosses 23 on opposite sides of the casing 10. Keyed on the crank shaft 21 is a worm gear 24 meshing with and driven by a worm 25 fast on a horizontal shaft 26 journalled in the side walls of the casing 10 at right angles to the axis of the crank shaft 21. Antifriction bearings 27 are preferably employed for the shaft 26, as shown in Fig. 1. One end of the shaft 26 is connected by a coupling 28 to the shaft of the electric motor 12.

35 From the foregoing it will be evident that the continuous running of the motor in one direction will effect vertical reciprocations of the jack plunger.

Depending from the cap 13 of the casing and preferably integral therewith is a hollow spring support 29, on the bottom of which is stepped the lower end of a coil spring 30. The upper end of the spring 30 bears directly on the lower side of the cross-head ring 17, and to permit vertical reciprocations of the cross-head 17, the end portions 18 of the latter extend through vertical slots 31 in the opposite sides of the spring support 29 being guided in said slots by blocks 32 on the end portions 18 of the cross-head, which blocks slidably engage the walls of the slots. The ends of the cross-head are threaded to receive nuts 33, and the portions of the casing 10 opposite the ends of the cross-head have openings covered by removable closures 34 to permit access to the nuts 33.

In Fig. 3 the cross-head 18 is shown at the limit of its up position which corresponds to the fully raised position of the load carried by the jack. In the reverse or fully lowered position of the load, the cross-head 18 is fully lowered; and the strength of the spring 30 is such that when it is fully tensioned its force is approximately equal to the gravity force of the load, the spring preferably being at all times under considerable tension, which, of course, is at its maximum when the spring is fully compressed.

From the foregoing it will be seen that, assuming the jack plunger and cross-head to be at the lowermost position, when the lifting action begins the power of the motor is supplemented by the upward thrust of the fully tensioned spring 30 which is approximately equal to the weight of the load; the power given off by the spring, of course, gradually lessening as it expands. During the lowering movement of the jack plunger and the load, the spring 30 is recompressed by the weight of the load, the only draft on the motor being to overcome the friction of the self-locking gears 24, 25. Thus, for the lifting movement, only enough power is required of the motor to overcome the friction of the self-locking gears 24, 25 and supplement the power of the spring 30, and, for the lowering movement only enough power is required of the motor to overcome the friction of the self-locking gearing and permit the weight of the load to restore the spring to its maximum tension. Manifestly, this means a large saving of the power output of the motor.

Fig. 2 illustrates a manually adjustable upper section of the jack plunger for the purpose of initially entering the same beneath the load, such as an automobile chassis bar to be lifted. Screwed onto the upper end of the lower plunger section 16 is an intermediate section 35, and telescoping within the section 35 is an upper tubular section 36. A collar 37 encircles the upper section 36, and the lower half of this collar is counter-bored to encircle the upper end of the intermediate section 35 and is secured to the latter by set screws 38. In the upper section 36 are vertically spaced holes 39, the function of which is later described. Secured on the upper end of the upper section 36 is a nut 40 engaged with a threaded rod 41 that extends some distance into the upper end of the section 36. Nut 40 is non-rotatably secured to the section 36 by set screws 42. A head 43 has on its lower side a socketed lug 44 which fits over the upper end of screw 41 and is secured to the latter by a cross pin 45. A saddle 46 is removably mounted on the head 43, the saddle having a central depending lug 47 fitting into a central socket 48 in the head 43, and lateral lugs 49 on each side thereof that are straddled by upstanding lugs 50 on the ends of the head 43.

Encircling the upper tubular plunger section 36 is the hub 51 of a hand wheel 52, said hub being formed with a depending integral annular flange 53 carrying cap screws 54, the inner ends of which enter an annular groove 55 in the collar 37, to lock the hand wheel 52 against vertical displacement from the collar while permitting it to turn relatively to the collar. In the hub 51 of the hand wheel is a pair of op-

positely disposed vertical slots 56 through which and one of the holes 39 is inserted a locking pin 57. This pin 57 locks the hand wheel to the upper tubular plunger section 36, and, since the nut 40 is non-rotatably mounted on the upper end of the plunger section 36, and the upper end of the screw 41 is non-rotatably engaged with the head 43, rotation of the hand wheel 52 raises or lowers the head and saddle. This is to obtain a final fine adjustment of the saddle with the chassis frame, vehicle spring, or other part engaged thereby. A preliminary coarse adjustment is readily effected by withdrawing pin 57, grasping the nut 40 and bodily raising or lowering the plunger section 36 until another hole 39 registers with the slots 56, and then reinserting the pin 57.

The last above described means for lengthening or shortening the plunger to adapt its upper end to a fit on the part to be lifted, is shown, described and claimed in my co-pending application on a combined vehicle lifting and rocking device, Serial No. 270,382, filed April 27, 1939, and no claim thereto is made herein.

Modifications and changes of the details of structure and arrangement may be resorted to within the scope and coverage of the appended claims, without departing from the principle of the invention or sacrificing any of the advantages thereof.

I claim:

1. In a jack of the class described, the combination with a casing having a cap, and a vertical plunger extending through and guided by said cap, of a spring support depending from said cap, a cross-head extending across said spring support and secured to said plunger, an electric motor and a power transmission means from said motor to said cross-head for reciprocating the latter, and a tensioned coil spring having a force when fully tensioned approximately equal to the gravity force of the load raised by the jack, said spring being stepped on said spring support with its upper end in thrust engagement with said cross-head.

2. In a jack of the class described, the combination with a casing having a cap, and a vertical plunger extending through and guided by said cap, of a spring support depending from said cap, a cross-head extending across said spring support and secured to said plunger, a crank shaft journaled in and between the sides of said casing below said spring support, links connecting said crank shaft with said cross-head, a worm wheel fast on said crank shaft, a worm in driving engagement with said worm wheel, an electric motor driving said worm, and a tensioned coil spring having a force when fully tensioned approximately equal to the gravity force of the load raised by the jack, said spring being stepped on said spring support with its upper end in thrust engagement with said cross-head.

3. A specific embodiment of the combination defined in claim 2, wherein the spring support is formed with vertical slots in its opposed side walls, the cross-head extends through and is guided by said slots, and the links are connected to the end portions of the cross-head on the outer sides of said slots.

EDMUND ARON.
